[57] CLAIM

The ornamental design for a half goblet, as shown and described.

DESCRIPTION

FIG. 1 is a left side perspective view of a half goblet showing my new design;

FIG. 2 is a front view of the half goblet of FIG. 1;

FIG. 3 is a right side view thereof;

FIG. 4 is a rear view thereof;

FIG. 5 is a left side view thereof;

FIG. 6 is a top plan thereof; and,

FIG. 7 is a bottom plan thereof.

The half-section is configured so that two identical half-sections can be brought together, as shown in FIG. 1, to form a complete goblet.

The broken line showing of the other half of the goblet in FIG. 1 is for illustrative purposes only and forms no part of the claimed design.
